SUPPORT STAND FOR A HOUSEHOLD APPLIANCE

Thomas R. Smith and Tad B. Anthony, Newton, Iowa, assignors to The Maytag Company, Newton, Iowa

Filed June 5, 1970, Ser. No. 23,327

Term of patent 14 years

Int. Cl. D6—99

U.S. Cl. D33—3

FIG. 1 is a perspective view of a support stand for a household appliance showing our new design;

FIG. 2 is a top view of the support stand for a household appliance shown in FIG. 1;

FIG. 3 is a side elevation view of the support stand for a household appliance shown in FIG. 1; and

FIG. 4 is a front elevation view of the support stand for a household appliance shown in FIG. 1.

We claim:

The ornamental design for a support stand for a household appliance, as shown.
